SUPPORTING PEDESTAL FOR SHIPPING CONTAINERS

Stephen G. Peterson, 6038 Westwood Terrace,
Norfolk, Va. 23508

Filed Mar. 19, 1970, Ser. No. 21,964

Term of patent 14 years

Int. Cl. D12—16

U.S. Cl. D66—2

FIG. 4

FIG. 5

FIG. 6

FIG. 7

FIG. 1 is a perspective view of a supporting pedestal for shipping containers;

FIG. 2 is a side elevational view of the right side of **FIG. 1**;

FIG. 3 is a bottom view;

FIG. 4 is a front view;

FIG. 5 is a side elevational view of the left side of **FIG. 1**;

FIG. 6 is a rear view; and

FIG. 7 is a top plan view.

I claim:

The ornamental design for a supporting pedestal for shipping containers, as shown.
